UNITED STATES PATENT OFFICE.

ALFRED PAPILLON, OF LOWRY, LOUISIANA.

OIL-BURNER.

1,130,194.

Specification of Letters Patent. Patented Mar. 2, 1915.

Application filed December 21, 1912. Serial No. 739,504.

To all whom it may concern:

Be it known that I, ALFRED PAPILLON, a citizen of the United States, residing at Lowry, in the parish of Calcasieu and State of Louisiana, have invented certain new and useful Improvements in Oil-Burners; and I do hereby declare the following to be a full, clear, and exact description of the invention, such as will enable others skilled in the art to which it appertains to make and use the same.

This invention relates to improvements in oil burners, the main and primary object of the same being to provide a burner of simple construction wherein the oil is thoroughly atomized upon being discharged into the zone of the propelling agent, the latter and the oil being separately fed to the burner.

A further object of the present invention is the provision of an oil burner the parts of which are so related and associated that a preliminary heating is imparted to the oil prior to its discharge from the burner, thereby rendering the oil more susceptible to atomization.

The invention also contemplates the provision of an oil burner the construction of which is such that the propelling agent for the oil, preferably steam, is emitted from the burner in a film or sheet into which the oil is discharged, and thereby carried to a suitable atomizing instrumentality, there to be broken up and spread out in a finely-divided mass, and thus to promote to a higher degree the combustion of the vapor so produced.

With these general objects in view, and others which will appear as the nature of the improvements is better understood, the invention consists substantially in the novel construction, combination and arrangement of parts, hereinafter fully described, illustrated in the accompanying drawings, and pointed out in the appended claims.

In the drawings Figure 1 is a side elevation of an oil burner embodying the herein-described invention. Fig. 2 is a top plan view of the mixing and atomizing instrumentality. Fig. 3 is a longitudinal sectional view through the body of the burner and illustrating its internal construction. Fig. 4 is a side elevation of another form of the burner. Fig. 5 is a top plan view of the mixing and atomizing instrumentality employed in the form illustrated in Fig. 4.

Fig. 6 is a longitudinal sectional view illustrating the relation of the oil-feed pipe of the form illustrated in Fig. 4 to the surrounding heating chamber.

60

Referring in detail to the accompanying drawings, and more particularly to Figs. 1, 2 and 3 thereof, the numeral 10 designates the body of the herein-described burner.

65

This is in the form of a four-way connection. Threaded into the top port of the connection 10 is an elbow 11 to which is connected a pipe 12, and said pipe 12 leads from any suitable source of steam supply, and may be controlled by any suitable form of 70 valve (not shown). At the lower port of the connection 10 is an elbow 13, the lower end of which is projected to the front of the body 10, and steam may, therefore, freely circulate from the pipe 12 through the body 75 10, and into the elbow 13, as is evident from an inspection of Fig. 3. To the rear port of the body 10 is connected a pipe 14, which pipe leads from a suitable source of oil supply, and said pipe may be controlled by a 80 valve (not shown) in order to regulate or cut off entirely the flow of the oil through this pipe. By referring again to Fig. 3, it will be noted that the pipe 14 extends through the body 10 to the forward port of said 85 body, and thus the pipe 14 is in the path of the steam as it flows through the body 10. By reason of this the oil in the pipe 14 is given a heating preliminarily to its discharge from the burner, the steam in the 90 body 10 surrounding the pipe 14, and thereby raising the temperature thereof. Connected to the forward port of the body 10 is a nipple 15 to which is connected a down- 95

wardly-directed elbow 16, and in the lower end of the elbow 16 is screwed a reducing bushing 17 in which is mounted a nozzle 18 the diameter of which is considerably less than the diameter of the elbow 16. The oil will, therefore, discharge from the pipe 14 100 through the nipple 15 and elbow 16, and be directed in a downward direction by the nozzle 18, and when discharged by the latter the oil is intercepted by the steam which passes through the body 10 and the elbow 105 13. For the purpose of this interception there is associated with the elbow 13 a mixing and atomizing instrumentality designated as an entirety by the numeral 19. It includes a nipple 20 which has a screw- 110 threaded engagement with the elbow 13, the forward end of the nipple 20 terminating in

a flared mouthpiece 21 through which the steam is adapted to discharge in a thin film or sheet, and extending forwardly from the nipple 20 is a mixing plate 22, of extended area, this plate lying beneath the nozzle 18, and receiving the oil discharged therefrom. In the discharge of the steam from the mouthpiece 21 the same follows the surface of the mixing-plate 22, and at the forward 10 end of the plate 22 is arranged a cup-shaped deflector 23 which extends at an angle of substantially forty-five degrees to the plane of the plate 22. Hence, as the steam with the body of oil which it has intercepted 15 from the nozzle 18 is projected against the deflector 23, the same is broken up and thoroughly atomized, and spread out in a finely-divided mass, and thus promotes to a higher degree the combustion of the vapor 20 which is so produced.

Referring now to the form of the burner illustrated in Figs. 4, 5 and 6, it will be noted that the mixing and vaporizing instrumentality is the same in this form as illustrated in Figs. 1, 2 and 3. The body of the burner, however, is different, the form illustrated in Figs. 4, 5 and 6 being designed for use in furnaces of the smaller sizes. The nipple 15 is connected to a T-connection 24 with which is engaged a nipple 25, and said nipple 25 is threaded to a T-connection 26 which leads from a suitable oil supply 27 which may be controlled by a suitable valve. The nipple 20 of the mixing and atomizing instrumentality is engaged with a T-connection 28, and this communicates with the T-connection 24 by an interposed nipple 29. To the rear end of the T-connection 28 is a reducing bushing 30 with which connects a nipple 31, and this nipple 31 is engaged by a suitable bushing 32 with a T-connection 33, the latter, in turn, being connected to a suitable source of steam supply 34. The T-connection 33 engages with a threaded connecting plug 35, said plug 35 being threaded in a reducing bushing 36 which is carried by the T-connection 26, and thus the T-connection 33 is sustained by the T-connection 26, and maintained in proper relation 45 for feeding the steam to the T-connections 28 and 24.

By an inspection of Fig. 6, it will be observed that the nipple 25 extends through the T-connection 24, being of less diameter 55 than the latter, and communicates with the nipple 15. Hence, the steam which is admitted to the T-connection 28 passes into the T-connection 24, and surrounds the nipple 25, and by reason of this the oil is preliminarily heated as it passes through the nipple 25 prior to its discharge from the burner.

In the operation of the herein-described burner, the oil issues from the nozzle 18, and is caught by the mixing-plate 22. As 65 the steam issues from the mouthpiece 21 in

the thin film or sheet referred to, it passes over the plate 22, and catches the oil, and the latter, propelled by the steam, is projected against the cup-shaped deflector 23, and is broken up by this deflector into a finely divided mass. The force with which the oil is projected against the deflector 23, is, of course, controlled by the pressure of the steam, and its volume, and in accordance with this pressure is the subdivision of the 70 mixture regulated.

The burner is, of course, properly positioned within a furnace so that combustion may take place therein, but as the furnace forms no part of the present invention it has 80 not been deemed necessary to illustrate the same.

Having thus described the invention, what is claimed as new, and desired to be secured by Letters Patent, is:

1. In a burner of the class described, the combination with a discharge nozzle, and an oil supply connected thereto, of a plate arranged across the path of discharge of said nozzle to receive the oil therefrom, a 90 nipple associated with said plate and provided with an opening through which a propelling agent may be discharged onto said plate to take up the oil discharged thereagainst, and means carried by said plate 95 against which the combined oil and propelling agent are projected to be atomized.

2. In a burner of the class described, the combination with a discharge nozzle, and an oil supply connected thereto, of a plate 100 arranged across the path of discharge of said nozzle to receive the oil therefrom, a nipple associated with said plate and provided with an opening through which a propelling agent may be discharged onto said 105 plate to take up the oil discharged thereagainst, and a deflector carried by said plate and arranged at a point beyond the nozzle for the combined oil and propelling agent to be projected thereagainst for atomization.

3. In a burner of the class described, the combination with a discharge nozzle, and an oil supply connected thereto, of a plate arranged across the path of discharge of said nozzle to receive the oil therefrom, a nipple 115 associated with said plate and provided with an opening through which a propelling agent may be discharged onto said plate to take up the oil discharged thereagainst, and a cup-shaped deflector carried by said plate 120 and arranged at a point beyond the nozzle for the combined oil and propelling agent to be projected thereagainst for atomization.

4. In a burner of the class described, the 125 combination with a discharge nozzle, and an oil pipe connected thereto, of a chambered connection through which said oil pipe passes, a steam supply connected to said chambered connection for heating the 130

oil pipe, a plate arranged across the path of discharge of said nozzle to receive the oil therefrom, a tubular connection between said plate and said chambered connection for conducting the steam from the latter to said plate for propelling the oil discharged against said plate, and means also carried by said plate and against which the combined oil and steam are projected for atomization.

5. In a burner of the class described, the combination with a discharge nozzle, and an oil pipe connected thereto, of a heating chamber surrounding said oil pipe, a steam supply connected to said chamber for heating the latter, a tubular connection also connected to said heating chamber, a plate supported by said tubular connection across the path of discharge of said nozzle to receive the oil therefrom, said plate serving to guide the steam discharged from said tubular connection, and a deflector also associated with said plate and against which the combined oil and steam are projected for atomization.

6. In a burner of the class described, the combination with a plate, of a nozzle supported opposite to said plate and adapted to discharge a body of oil thereagainst, a pipe connected to said nozzle for feeding oil thereto, a steam connection associated with said plate at one side of said nozzle and adapted to project a body of steam along said plate and across the path of discharge of said nozzle, and a deflector arranged at the side of the nozzle opposite to the location of said steam connection and against which the combined oil and steam are projected for atomization.

40 7. In a burner of the class described, the combination with a plate, of a nozzle supported in a position to discharge against said plate, an oil supply connected to said nozzle, a steam connection arranged at one end of said plate for discharging a body of steam along the latter and across the path of discharge of said nozzle, and means at the other end of said plate for effecting atomization of the combined oil and steam.

50 8. In a burner of the class described, the combination with a plate, of a nozzle supported to discharge against said plate, an oil supply connected to said nozzle, a nipple arranged at one side of said discharge nozzle and connected to a steam supply, said nipple having a mouth arranged to discharge on said plate and direct a body of steam across the path of discharge of said nozzle,

and means arranged opposite to said nipple for atomizing the combined oil and steam.

5. In a burner of the class described, the combination with a plate, of a nozzle supported to discharge against said plate, an oil supply connected to said nozzle, a nipple arranged at one side of said discharge nozzle and connected to a steam supply, said nipple having a mouth extending transversely of said plate and arranged to discharge a body of steam on the surface of said plate toward which said nozzle discharges, and means arranged opposite to said nipple for atomizing the combined oil and steam.

10. In a burner of the class described, the combination with a plate, of a nozzle supported to discharge against said plate, an oil supply connected to said nozzle, a nipple arranged at one side of said discharge nozzle and connected to a steam supply, said nipple having a mouth extending transversely of said plate and arranged to discharge a body of steam on the surface of said plate toward which said nozzle discharges, and an inclined cup-shaped deflector arranged opposite to said nipple for atomizing the combined oil and steam.

11. In a burner of the class described, the combination with a heating chamber provided with oppositely-disposed pairs of ports arranged with the pairs at right angles to each other, of an oil pipe connected to one pair of said ports and extending through said chamber, a discharge nozzle associated with said oil pipe, a steam supply connected to one of the other ports for feeding steam to said chamber, a tubular connection arranged in the port opposite to said steam supply and provided with a mouth for permitting discharge of the steam from said chamber, a plate supported by said tubular connection across the path of discharge of said nozzle, the mouth of said tubular connection being arranged to discharge the steam against the surface of said plate toward which said nozzle discharges, and means associated with said plate opposite to said tubular connection and against which the combined oil and steam are discharged for atomization.

In testimony whereof I affix my signature, 110
in the presence of two witnesses.

ALFRED PAPILLON.
